BY

ATTORNEY

UNITED STATES PATENT OFFICE.

MORRIS V. HUBBARD, OF SAN JOSE, CALIFORNIA.

STRETCHER.

1,396,208.

Specification of Letters Patent.

Patented Nov. 8, 1921.

Application filed November 28, 1920. Serial No. 426,618.

To all whom it may concern:

Be it known that I, MORRIS V. HUBBARD, a citizen of the United States, and resident of San Jose, in the county of Santa Clara and State of California, have invented certain new and useful Improvements in Stretchers, of which the following is a specification.

It is the object of my invention to provide a stretcher that may be readily adapted for use as a flexible sling stretcher, a rigid sling stretcher, or a rigid frame stretcher; that can be quickly and easily placed under lateral tension, assembled or disassembled according to the purpose for which it is to be used; that will be greatly strengthened in the parts subjected to greatest strains, and that will be substantial and durable in its practical application.

20 In the drawing:

Figure 1 is a plan view of my invention assembled as a rigid frame stretcher.

Fig. 2 is a plan view of the same assembled in the form of a rigid sling.

25 Fig. 3 is a plan view of the same assembled in the form of a flexible sling.

Fig. 4 is an enlarged sectional view through the central portion of a side bar.

30 Fig. 5 is an enlarged sectional view showing method of connecting the side and end bars.

Fig. 6 is a detail of the end bar locking mechanism.

Referring more particularly to the drawing, 1-1 indicate the two side bars of the stretcher, each bar 1 being formed in three parts. These parts are preferably formed of pipes of suitable dimensions, the central part being a short member threaded as at 2-2 to engage the threaded ends 3-3 of the other two parts and extending into the other two parts a distance as to 4-4.

These bars 1-1 are separated by end bars 5-5, each end bar 5 being formed of two parts threaded as at 6 into a coupling or sleeve 7. On each end of bar 5 is formed a pin 8 having a square shoulder 9 to engage round and square orifices 10-11 in the end of side bars 1-1. Pin 8 is formed with 50 grooves in the end thereof as at 12 and a flat element as 13 is slidably mounted on bar 1 as at 14 and provided with a hole 15 and slot 16 for engaging grooves 12 and locking the bars 1 and 5 together. Bar 5 also has a 55 curved plate 17 formed on the ends thereof to engage the curved surfaces of bars 1-1

to more effectually prevent movement between the two bars.

A canvas 18 is shown divided lengthwise into two parts and provided with alternately spaced loops through which pass metallic straps 19 to normally hold them in fixed relation to each other. The canvas 18 is also provided with loops 20 engaging the two end portions of bars 1-1 and to which they 60 are normally secured in any suitable manner as by straps 21 engaging staples 22 on bars 1-1 and passing through loops 20.

In a stretcher constructed in this manner and assembled as described, a rigid frame 70 stretcher is provided that is strongest where the greatest strains are applied, that is, in the center of side bars 1-1, and the canvas is quickly and easily placed under the desired tension by the simple means of turning 75 sleeves 7.

There are occasions where it is impossible to properly handle a body on a rigid frame stretcher, such as, for instance, in ascending or descending a stairway having sharp turns. 80 In such a contingency the said bars 5-5 are quickly unlocked and removed whereupon a rigid sling is provided which can be folded around the body thereby so supporting the full length thereof that it can be carried in a 85 vertical position or at any angle thereto. There are also times when it is desirable to place a body in a sitting posture in a chair, or change the same from a chair to a bed. In this case the stretcher is readily adapted 90 to this unusual position by simply removing the central portion of the side bars thereby providing a flexible sling, the end bars 5-5 being removed or not as occasion may require. 95

It is thus seen that I have provided a stretcher that is quickly and easily adaptable to varied uses, and is simple, durable, and substantial in its practical application.

It is to be understood, of course, that 100 while I have herein shown and described one particular embodiment of my invention, changes in form, and construction may be made within the scope of the appended claims. 105

I claim:

1. A stretcher of the class described, comprising in combination a pair of side members, said side members each being divided longitudinally at a central point thereof, a 110 pair of coupling members for connecting the divided ends of said side members, a pair of

- 2
- cross members for connecting the similar ends of said pair of side members, said cross members each being longitudinally divided at a central point thereof, coupling 5 means for rigidly connecting the divided ends of said cross members, a pin extending from each end of the cross members, and adapted to extend through openings formed in the ends of said side members, and said 10 pins each having an annular groove formed at its outer end, and a slotted plate slidably mounted on the side members for each pin, and adapted to engage in the annular groove thereof and hold the side members to the 15 cross members.
2. A stretcher frame of the class described, comprising in combination a pair of side members, said members each being divided longitudinally at a central point, a 20 pair of coupling members for connecting the divided ends of said side members,

a pair of cross members for connecting the similar ends of said pair of side members, said cross members each being longitudinally divided at a central point thereof, coupling means for rigidly connecting the divided ends of said cross members, a pin extending from each end of the cross members and adapted to extend through openings formed in the ends of said side 25 members, and said pins each having an annular groove formed at its outer end, and a square shoulder at its inner end, said shoulder being adapted to extend into a similar recess or opening formed in the 30 inner side of the side members, and a slotted plate slidably mounted on the side members for each of the pins and adapted to engage in the annular groove thereof and hold the side members to the cross members.

MORRIS V. HUBBARD.
